UNITED STATES PATENT OFFICE.

MORRIS KLOSNER, OF NEW YORK, N. Y.

VERNIER INSTRUMENT.

Application filed October 16, 1922. Serial No. 594,684.

To all whom it may concern:

Be it known that I, MORRIS KLOSNER, a citizen of the United States, residing at New York, county of Bronx, State of New York, have made a certain new and useful Invention in Vernier Instruments, of which the following is a specification.

This invention relates to vernier apparatus, and more particularly electrical apparatus such as condensers, rheostats, etc. This application is a continuation in part of my application No. 540,783, filed Mar. 3, 1922.

The object of the invention is to provide an apparatus or instrumentality which permits a plurality of adjustments, and which is simple in structure, economical of manufacture, and efficient in operation.

A further object of the invention is to provide an apparatus of this character of molded material which is positive in operation, practical, indestructible, and presents a very pleasing appearance.

A further object of the invention is to provide separately movable control elements actuated from a single handle, wherein positive action is secured, but nevertheless the operating mechanism is concealed from view.

Further objects of the invention will appear more fully hereinafter.

The invention consists substantially in the construction, combination, location and relative arrangement of parts, all as will be more fully hereinafter set forth, as shown by the accompanying drawing, and finally pointed out in appended claims.

Referring to the drawing:

Fig. 1 is a front view of a vernier adjustment instrumentality embodying my invention as applied to a vernier rheostat.

Fig. 2 is a sectional view taken on the line 1, 2, Fig. 1, looking in the direction of the arrows.

Fig. 3 is a modified arrangement showing an adaptation of the principles of my invention to another electrical instrumentality, in this instance, a condenser.

The same part is designated by the same reference numeral wherever it occurs throughout the several views.

While I have shown, and will now describe, my invention as applied to a vernier rheostat, I wish it to be understood that the same is not to be limited or restricted thereto as the principles thereof may be

readily applied to various other types of apparatus, particularly in the electrical art, but in the arrangement shown as applied to a rheostat, reference character 1 designates 60 what is commonly termed the base, which supports the rough adjustment wire member 2. The base is circular in shape, as is the resistance wire element 2, and the base has around the periphery thereof the vernier 65 wire 3 connected in suitable electrical arrangements with the resistance wire 2 and the binding posts 4. The foregoing structure is now standard in the art, and is shown and described in detail in my copending 70 application, Serial No. 540,783, filed March 3, 1922, and per se forms no part of my present invention. The present invention consists of the novel means for securing variable contact with the resistance wire 2 75 and the vernier wire 3 by means of the respective contact arms 5 and 6. In the arrangement shown, contact arm 6 is secured to the end of a shaft 7, which extends through the base and the panel, or other 80 board, 8, on which the instrumentality is mounted. The end of the shaft 7 is secured to a handle or knob 9, which, in the form shown, is substantially cone-shaped, being formed with a tapering bore 10 therein, the 85 inner wall of which is provided with parallel and axially extending knurls. A set screw 11, preferably countersunk, secures the knob 9 to the shaft 7. The shaft 7 is provided with a sleeve 12, which likewise extends 90 through the base 1 and the board 8. A graduated dial, or the like, 13, is secured to the sleeve 12 in any suitable manner, for example, by means of the set screw 13^a, which is preferably countersunk in a cone-shaped lip extension 14, formed therewith or secured thereto. The periphery of the cone-shaped lip 14 is likewise provided with axially extending parallel knurls of the same shape and size as the interior knurls of the 95 knob 9. The shaft 7 is loosely mounted on the sleeve 12, and is of sufficient length so that the knob 9 may be pulled outwardly, whereby the interior knurls thereof are out of contact with the exterior knurls of the lip 14 on the member 13. Thereupon rotative movement imparted to the knob 9 will secure movement of the contact arm 6 alone, but when the knob 9 is forced towards the bore 8, so that the interior knurls thereof 100 are in mesh or contact with the exterior knurls of the lip 14 of member 13, then

rotative movement of the knob 9 secures simultaneous rotation of the contact arms 5 and 6.

I have found the foregoing structure to contain many practical advantages over other types of arrangements for securing control of two or more movable elements independently of each other from a single operating handle, and is particularly adaptable for use in connection with molded parts, which, as is well known, present a better appearance in a finished product than machined parts, also enabling the utilization of insulating material such as bakelite, or the like.

In Fig. 3 I have shown in place of the vernier rheostat a vernier condenser wherein the sleeve 12 carries thereon a plurality of rotatable condenser blades 20 which move relative to the plurality of stationary condenser blades 21. The shaft 7 in this instance controls a single condenser blade 23. Many other modifications and changes in detail will readily occur to those skilled in the art without departing from the spirit and scope of my invention as defined in the claims. But having now set forth the objects and nature of my invention, and having shown and described a structure embodying the principles thereof, what I claim as new and useful and of my own invention and desire to secure by Letters Patent is,—

1. In a vernier rheostat structure, and in combination with a rough adjustment resistance element and its contact finger, and a fine adjustment resistance element and its contact finger, and concentric shafts for operating said fingers, of knobs nested one within the other for operating said shafts, and means controlled by one knob for selectively operating its respective shaft alone, or both shafts together, through its nested engagement with the other of said knobs.

2. In a vernier rheostat structure, and in combination with a rough adjustment resistance element and its contact finger, and a fine adjustment resistance element and its contact finger, and concentric shafts for operating said fingers, of nested knobs for operating said shafts, and means for moving one of said knobs into and out of contact with the other to thereby move one of said shafts independently of or in unison with the other.

3. In a vernier rheostat structure, and in combination with a rough adjustment resistance element and its contact finger, and a fine adjustment resistance element and its contact finger, and concentric shafts for operating said fingers, of a knob provided with a beveled external surface and secured to one of said shafts, a second knob secured to the other shaft and provided with a beveled interior surface and adapted to encom-

pass at least a portion of said first mentioned knob, and means for moving said second knob into and out of contact with said first mentioned knob.

4. In a vernier rheostat structure, and in combination with a rough adjustment resistance element and its contact finger, and a fine adjustment resistance element and its contact finger, and concentric shafts for operating said fingers, of a knob provided with a beveled external surface and secured to one of said shafts, a second knob secured to the other shaft and provided with a beveled interior surface and adapted to encompass at least a portion of said first mentioned knob, and means for moving said second knob into and out of contact with said first mentioned knob, said knobs being provided with means to prevent movement relative to each other when in surface contact with each other.

5. In a vernier rheostat structure, and in combination with a rough adjustment resistance element and its contact finger, and a fine adjustment resistance element and its contact finger, and concentric shafts for operating said fingers, of a knob provided with a beveled external surface and secured to one of said shafts, a second knob secured to the other shaft and provided with a beveled interior surface and adapted to encompass at least a portion of said first mentioned knob, and means for moving said second knob into and out of contact with said first mentioned knob, the external surface of said first knob and the internal surface of the second knob being provided with cooperative knurls to prevent relative movement of said knobs when in contact with each other.

6. In a vernier rheostat structure, and in combination with a rough adjustment resistance element and its contact finger, and a fine adjustment resistance element and its contact finger, and concentric shafts for operating said fingers, of a knob provided with a beveled external surface and secured to one of said shafts, a second knob secured to the other shaft and provided with a beveled interior surface and adapted to encompass at least a portion of said first mentioned knob, and means for moving said second knob into and out of contact with said first mentioned knob, the external surface of said first knob and the internal surface of the second knob being provided with axially extending cooperative grooves to prevent relative movement of said knobs when in contact with each other.

In testimony whereof I have hereunto set my hand on this 13th day of October, A. D., 1922.

MORRIS KLOSNER.
